AUDIBLE VEHICLE BACK-UP ALARM

Rudolph M. Duris, Norwalk, Conn., assignor to
General Signal Corporation

Filed Oct. 4, 1974, Ser. No. 511,962

Term of patent 14 years

Int. Cl. D10—06

U.S. Cl. D10—116

FIG. 1

FIG. 2

FIG. 3

FIG. 4

FIG. 5

FIG. 1 is a front view of an audible vehicle back-up alarm, showing my new design.

FIG. 2 is a side view of the audible vehicle back-up alarm shown in FIG. 1, the side views of the audible vehicle back-up alarm being symmetrical.

FIG. 3 is a top view of FIG. 1.

FIG. 4 is a bottom view of FIG. 1.

FIG. 5 is a rear-view of the audible vehicle back-up alarm shown in FIG. 1.

I claim:

The ornamental design for an audible vehicle back-up alarm, as shown.
